SPRAYING DEVICE

Edward O. Norris, Westport, Conn.

Application April 3, 1946, Serial No. 659,236

6 Claims. (Cl. 299—63)

1

This invention relates generally to spraying apparatus of the centrifugal type wherein a liquid is fed by suitable means to an atomizing distributor, rotating at high speed, which receives, atomizes, and projects the liquid in a finely divided spray, through a suitable opening in the apparatus, against the surface to be sprayed.

More specifically, the invention relates to a portable centrifugal spraying apparatus of the so-called all position type which is capable of being operated at any angle, the general object of the invention being to provide a device of this character which is simple, compact, light and efficient in operation and which is especially adapted for use by relatively unskilled operators.

Another object of the invention is to provide a device of this character which contains a minimum number of operating parts.

Another object of the invention is to provide a portable spraying apparatus having a high speed rotary collecting case which is positively driven through suitable driving connections by a high speed motor, and a centrifugal atomizing distributor which is driven at a greater rotary speed than the speed of the case, through contact with the annular film of liquid held against the peripheral wall of the collecting case by centrifugal action.

Another object of the invention is to provide a portable spraying apparatus having a high speed collecting case in which the possibility of the liquid such as paint separating into its component parts of pigment and oil is eliminated.

Other and more limited objects of the invention will be apparent from the following specification and the accompanying drawings forming a part thereof wherein:

Fig. 1 is a side elevation of a portable spraying device constructed according to my invention;

Fig. 2 is a front elevation thereof;

Fig. 3 is an enlarged horizontal section taken on the line 3—3 of Fig. 2;

Fig. 4 is an enlarged vertical section taken on the line 4—4 of Fig. 2, the scale of Fig. 4 being less than the scale of Fig. 3;

Fig. 5 is a fragmentary transverse section taken substantially on the line 5—5 of Fig. 4;

Fig. 6 is a transverse section taken on the line 6—6 of Fig. 1;

Fig. 7 is a transverse section taken on the line 7—7 of Fig. 4;

Fig. 8 is a view similar to Fig. 3 showing a modified form of the device; and

Fig. 9 is a front elevation of the modified form,

2

parts being broken away and other parts being broken away for purposes of illustration.

My improved spraying apparatus comprises generally a rotating collecting case and a centrifugal distributor operatively disposed therein. The collecting case is rotated at approximately 10,000 revolutions per minute by a series type high speed motor enclosed in a suitable housing. The distributor is rotatably mounted within the collecting case with the periphery thereof in close proximity to the inner peripheral wall of the collecting case, with the plane of rotation thereof being at an acute angle to the plane of rotation of the collecting case. The liquid is fed into the collecting case, either by gravity from a container secured directly to the apparatus or by pressure through a flexible hose from a container remote from the apparatus. A control valve is provided to regulate the rate at which the liquid is fed into the collecting case. After the liquid enters the collecting case it is thrown by centrifugal action out against the inner peripheral wall of the case where it forms an annular film which rotates with the case. The periphery of the distributor is located in such close proximity to the inner peripheral wall of the collecting case that it dips into this film of liquid and is rotated thereby at approximately the same peripheral speed as the collecting case. But, since the diameter of the distributor is considerably less than the diameter of the collecting case, the distributor is driven a correspondingly higher speed than the collecting case. Since the plane of rotation of the distributor is disposed at an acute angle across the plane of rotation of the collecting case, the edge of the distributor cuts across the advancing film of liquid on the inner peripheral wall of the collecting case and agitates the liquid to prevent centrifugal separation of the liquid into its component parts, such as pigment and oil in the case of paint. As the annular film of liquid in the collecting case comes into contact with the distributor, a part thereof is first carried inwardly on the distributor towards the axis thereof and is then thrown by centrifugal action tangentially outward from the periphery of the distributor in a ring or band therearound. Part of this ring or band of spray is projected out through the open end of the collecting case, at an angle to the axis thereof, and the balance of the ring or band of spray is intercepted by the case and is returned to the annular peripheral film. Means are also provided through which the distributor is automatically thrown into or out of operative relationship

with the collecting case as liquid is admitted to or cut off therefrom.

Referring now to the drawings by reference characters, the numeral 1 indicates a motor housing in which is mounted a high speed series type motor having an armature shaft 2 which extends out through the forward end of the housing. A handle 3 by which the device is held and manipulated in operation is secured to and projects downwardly from the motor housing 1. A ring 4 which is removably secured to the forward end of the motor housing 1 has a casing 5 secured thereto by screws 6 (Fig. 3). The casing 5 has a centrally disposed circular opening 5a through the forward end thereof, with the plane of the opening disposed at an angle to the axis of the armature shaft 2 as is clearly shown in Figs. 1 and 3. A cup-shaped collecting case 7 having a hub 8 is secured to the projecting end of the armature shaft 2 by a nut 9. The collecting case 7 is mounted within the casing 5 with the forward end thereof partially projecting out through the opening 5a, and it comprises a base 10 formed integrally with a forwardly projecting curved annular wall 11. The forward end of the annular wall 11 is flanged inwardly as indicated at 12 and terminates in an opening 13 concentric with the axis of the armature shaft 2 and lying in a plane perpendicular to the axis of the armature shaft 2 and angularly disposed with respect to the plane of the opening 5a. A frusto-conical cut-off ring 14 is concentrically secured to the collecting case 7 within the opening 13 by a plurality of legs 15. The collecting case 7 has a chamber 16 therein between the base 10 and a semi-spherical rear wall 17 of the case. An annular series of spaced inclined openings 18 provide communication between the chamber 16 and the interior of the case 7 forwardly of the base 10.

A centrifugal distributor 20 is rotatably mounted within the collecting case 7 with the periphery thereof in close proximity to the inner peripheral wall 11 as indicated at 21 in Figs. 4 and 5. The axis of the distributor is disposed at an angle to the axis of the collecting case 7 and lies in a horizontal plane above the axis of the case 7, as is clearly shown in Figs. 2, 3 and 4. The plane of rotation of the distributor 20 is disposed at an angle to the plane of the opening 13 of the collecting case and intersects the opening 13. The distributor 20 includes a disc 22 having an in-turned peripheral flange 23 and a hub 24 which extends inwardly and outwardly therefrom. A supplemental disc 25 having a peripheral flange 26 is secured to the inner face of the disc 22, by screws 27, in spaced relation so as to provide an annular space 28 between the discs 22 and 25. The inner end of the hub 24 has an axial bore 29 in which is secured the reduced end 30 of a shaft 31 which is slidably and rotatably mounted in a bushing 32 rigidly secured by a pin 33 in a boss 34. The boss 34 is formed integrally with a plate 35 which is secured to the outer end of a semi-circular support 36 secured to and projecting forwardly from the ring 4 about the casing 5. The bushing 32 extends into a bore 38 in the forward end of the hub 24. The shaft 31 has an axial bore 39 therein, and has a threaded outer end which extends out beyond the end of the bushing 32 within the boss 34. A nut 40 on the threaded end of the shaft 31 permits a limited axial movement of the shaft 31 within the bushing 32. A screw 41 having a knurled adjusting head 42 extends through a threaded aperture in the end of the boss 34 and projects into the

bore 39 in the shaft 31. A spring 43 and a ball 44 are disposed, as shown in Fig. 3, within the bore 39 in the shaft 31. When the feeding of liquid to the collecting case 7 is cut off, as is hereinafter described, the spring 43 urges the distributor from the position shown in full lines in Fig. 3 to the position shown in dotted lines therein. But as soon as the feeding of liquid is resumed, the pressure of the liquid film causes the distributor to snap back to the full line operative position, shown in Fig. 3, against the pressure of the spring 43. The pressure of the spring 43 may be varied by adjusting the screw 41. A spring 45 is provided to retain the screw 41 in adjusted position.

The manner and mechanism for supplying and controlling the feeding of liquid to the interior of the collecting case 7 will now be described. A ring-shaped cup generally indicated by the numeral 46 is disposed about the hub 8 of the collecting case 7 between the forward end of the motor housing 1 and the rear wall 17 of the collecting case. The cup 46 is suitably secured to the ring 4 and comprises a rear wall 47 and inner and outer annular side walls 48 and 49 which extend forwardly from the rear wall 47. The forward open end 50 of the cup 46 extends into the chamber 16 through an opening 51 in the rear wall 17 of the collecting case. A valve body 52, having chambers 53 and 54 therein which are connected by a passageway 55, is secured to the outer wall 49 of the cup 46. The chamber 54 communicates with the cup 46 through a port 56. A valve disc 57 which is operative to open or close the passageway 55 is secured within the chamber 54 to the inner end of a valve stem 58 which extends out from the valve body 52 through a packing gland 59. A spring 60 within the chamber 54 normally urges the valve 57 into position to close the passageway 55 as shown in Fig. 6. Liquid is fed into the chamber 53 through a tube 61 which is secured to and projects upwardly from the valve body 52. A threaded coupling 62 is secured to the upper end of the tube 61. Liquid may be supplied to the chamber 53 in either of two ways as desired. As shown herein the liquid is fed by gravity from a container 63 which is removably swivelly secured to the coupling 62. But if desired liquid may be supplied under pressure from a remote container through a flexible hose connected to the tube 61 by the coupling 62. The movement of the valve 57 to open the passageway 55 is effected by the operator through a lever 64 which is pinned to one end of a shaft 65 rotatably supported by brackets 66 projecting out from the motor housing 1. The other end of the shaft 65 has an arm 67 pinned thereto which extends downwardly therefrom in alignment with the valve stem 58. Movement of lever 64 towards the handle 3 will rock the shaft 65, which through the arm 67 and valve stem 58 will move the valve 57 to open the passageway 55. The rate at which liquid is fed is dependent upon the distance the valve 57 is moved from the end of the passageway 55 within the chamber 54. An adjustable stop 68 is provided to limit the movement of the lever 64 and consequently the maximum opening of the valve 57.

Operation

When the passageway 55 is opened, liquid will flow from the chamber 53 into the chamber 54 and thence through the port 56 into the cup 46. From the cup 46 the liquid will flow through the open end 50 thereof into the chamber 16. Cen-

trifugal action will force the liquid in the chamber 16 out against the outer spherical wall thereof and through the inclined openings 18 into the interior of the collecting case 7. As the liquid enters the collecting case through the openings 18 it is thrown by centrifugal action against the inner peripheral wall 11 about which it forms a film which rotates with the collecting case. The periphery of the distributor discs 22 and 25 dip into this film of liquid and are rotated thereby at approximately the same peripheral speed as the collecting case. Due to the angular relationship between the plane of rotation of the collecting case and the plane of rotation of the distributor discs, the liquid is highly agitated as it comes into contact with the distributor discs. This agitation prevents centrifugal separation of the liquid into its component parts which would otherwise occur if the liquid is non-homogenous due to the high speed of rotation of the collecting case. As the liquid contacts the distributor discs it first travels inwardly thereon towards the axis thereof and then is thrown tangentially therefrom in a ring or band of finely atomized spray completely surrounding the distributor discs. A portion of this band of atomized spray is projected out through the cut off ring 14 and the balance thereof is intercepted by and retained within the collecting case for re-spraying. The flange 12 and cut-off ring 14 are so shaped and disposed with respect to the collecting case that any spray striking them will be returned to the collecting case. As soon as the feeding of liquid to the collecting case is stopped by the valve 57 the distributor is moved from the full line position to the dotted line position, as shown in Fig. 3, by the spring 43. But, as previously stated, when the feeding of liquid is resumed the distributor immediately snaps back to the full line operative position against the pressure of the spring 43.

In Figs. 8 and 9 I have shown means whereby the distributor is mechanically thrown into and out of operative relationship with the collecting case as liquid is admitted to or cut off therefrom. In these figures the distributor and the mechanism for rotatably supporting it within the collecting case are slightly modified. The balance of the device is the same as is shown in Figs. 1 to 7 and the same reference numerals are applied thereto.

Referring now to Figs. 8 and 9. In the construction shown in this form I employ a distributor 70 which consists of a single disc 71, similar to the disc 22, which has an annular flange 73 and is secured to a shaft 74. The distributor 70, when in operative position, is disposed in the same relationship to the collecting case 7 as is the distributor 20, so that when in operation it will project a portion of a band of atomized spray out through the open end of the collecting case 7 in the same manner as the distributor 20. The shaft 74 is rotatably mounted in a bore 75 in a bushing 76 which is rotatably mounted in a boss 77 integral with the plate 35. The shaft 74 is retained in the bushing 76 by a collar 78 on the end thereof and the bushing 76 is held in the boss 77 by a collar 79 on the outer end thereof. The axis of the bore 75 in the bushing 76 is disposed at an angle to the axis of the bushing as is clearly shown in Fig. 8. An arm 80 secured to the collar 79 is pivotally connected as by a ball and socket joint 81 to one end of a link 82. The other end of the link 82 is connected by a ball and socket joint 83 to an arm 84 secured to the extended end 85 of the shaft 65.

Thus, when the shaft 65 is rocked to open or close the passageway 55 controlling the admission of liquid into the collecting case 7, the bushing 76 is also rotated in the boss 77, which moves the distributor between the full line and dotted line positions shown in Fig. 8. When the distributor is in the full line position, which is the operative position, it will project spray out through the open end of the collecting case; but when it is in the dotted line position, all of the spray thrown out from the periphery of the distributor will be intercepted by and retained within the collecting case. The arrangement of the bushing 76 within the boss 77 and the connections between the bushing 76 and the shaft 65 is such that when the passageway 55 is closed by the valve 57 to prevent feeding of liquid to the collecting case 7 the distributor 70 will be in the dotted line inoperative position (Fig. 8), and when the lever 64 is operated to open the passageway 55 to admit liquid to the collecting case the distributor will be moved from the inoperative dotted position to the full line operative position (Fig. 8).

Although the apparatus is particularly adapted for paint spraying, as it is obvious that the apparatus can be used equally well for atomizing and spraying other liquids, such as a liquid disinfectant.

It is to be understood that my invention is not limited to the specific construction shown and described herein as various modifications can be made therein within the scope of the appended claims.

What is claimed is:

35. 1. In a spraying apparatus, a rotary collecting case having an annular peripheral wall forming a channel for receiving a spray forming material and having an axial spray opening, means supplying a spray forming material to said case, means driving said case to cause the material to form a rotating peripheral layer on said wall, a distributor comprising a disc, means rotatably mounting said disc in said case with its peripheral edge dipping into said peripheral layer of material with its axis of rotation at an angle less than normal to the axis of rotation of said case, and with the plane of rotation of the disc intersecting said spray opening, said disc being constructed and arranged to be driven by the rotating layer of material and to pick up material therefrom and discharge the same centrifugally as a spray, a portion of which passes out through said spray opening and the remainder of which is intercepted by said collecting case and returned to said peripheral layer.
40. 2. A spraying device as set forth in claim 1 in which the means supplying material to the case comprises a member having an annular chamber coaxial with said case and rotatable therewith, having radially inclined passages extending from said chamber to said case to feed said material centrifugally to said case and having a supply passage feeding said material to said chamber.
45. 3. A spraying device as set forth in claim 2 in which said member has a stationary annular passage coaxial with said annular chamber and opening thereto and a supply pipe is connected to feed said material to said last passage.
50. 4. A spraying device as set forth in claim 1 in which said distributor is mounted to be shifted into non-spraying position and manual means is connected to control both the shifting of said distributor and the supply of said material to said case in a sense to cut off the feed and render

the distributor inoperative for spraying when said manual means is actuated.

5. In a spraying device as set forth in claim 1, a support carrying said distributor, spring means on said support urging said distributor to non-spraying position and compressible under the pressure of the layer of said material to allow said distributor to shift on said support to spraying position.

6. In a spraying device as set forth in claim 1, a shaft carrying said distributor, a support carrying a rotatable bushing, said shaft being mounted in and non-coaxial with said bushing, and a manual control member connected to rotate said bushing.
